UNITED STATES PATENT OFFICE.

FRANK LEAKE, OF PHILADELPHIA, PENNSYLVANIA.

TERRY-LOOM.

SPECIFICATION forming part of Letters Patent No. 372,920, dated November 8, 1887.

Application filed October 6, 1886. Serial No. 215,434. (No model.)

To all whom it may concern:

Be it known that I, FRANK LEAKE, of Philadelphia, in the county of Philadelphia and State of Pennsylvania, have invented a new 5 and useful Improvement in Terry-Looms; and I do hereby declare that the following is a full, clear, and exact description of the same.

My invention is an improvement in looms designed for weaving terry cloths and pile or 10 looped fabrics of all kinds, and relates especially to mechanism for automatically controlling the putting on and off of the terry pile or loop, so that a fabric of any desired pattern may be produced.

15 My invention is applicable to the form of terry motion shown in Letters Patent granted to J. and C. Rothwell, No. 257,517. In this device the lay is so controlled that in a certain number of beats thereof the movement will 20 not be up to the cloth-making line, but each successive pick of filling thrown in during this time will be beaten closely against the pick just preceding. The next beat, however, after the required number of picks have been made 25 will carry the lay and reed to the cloth-line, and the intervening portions of the terry-warp threads, which are drawn from a loose roller, are caused to rise or pucker, forming the pile or loop of the terry fabrics in the usual manner. To effect these movements an eccentric 30 is employed for the bearing of the crank-shaft, which is turned through suitable connections to alter the position of the lay crank-shaft forward and backward to vary the 35 amount of the beats at the proper moment. In the latter position the lay beats only partially up, while in the former the beat is all the way. These movements follow each other alternately to form the terry, as mentioned.

40 In the accompanying drawings, Figure 1 is a plan view of so much of a terry-loom as is necessary for a full understanding of my improvement, a portion of the lay being broken away in order to show the devices situated directly 45 beneath the same. Fig. 2 is a section on line $\times \times$ of Fig. 1, the mechanism shown being adapted to weave a fabric of regular pattern, and the parts being in position to form the terry. Fig. 3 is a similar view with the 50 mechanism in position to complete the terry or continue the weaving plain, and thus miss

a terry. Figs. 4 and 5 are views similar to Figs. 1 and 3, showing the manner of applying the mechanism employed for weaving a fabric of variable pattern.

55 In the drawings the main frame of the machine is shown at A A. The lay B is pivotally connected to the frame at its lower end, and is operated in the usual manner from the crank-shaft C. This shaft is journaled eccentrically in bearings B', so that movement of the said bearings within their boxes will affect the position of the crank-shaft and the amount of beat of the lay, according as the movement of said bearings be forward or backward. 60

65 The mechanism for operating the eccentric is substantially the same as shown and described in said patent, and may be briefly described as follows: An arm, O, secured to the eccentric, is connected through rod P to an 70 arm, N, of a rock-shaft, L, journaled in the rear of the frame. An additional arm, I, of the rock-shaft is, through the intermediate link H, actuated by a lever, G, pivoted to the girt A'. An arm, 1, depending from this lever receives one end of a powerful spring, M, the 75 opposite end of which is attached to the frame of the machine. It will be clearly seen that the force of the spring exerted upon the arm 1, will (when not resisted) actuate the lever G 80 and throw it to the limit of its upward movement, which action will, through the intermediate connections just described, move the eccentric to its backward position, thus permitting the lay to make only partial beats up. 85 The movement of the parts is limited by the lever striking the projecting end of the auxiliary cam-shaft e. In order to complete the formation of the terry, it is necessary that the lay should make a full beat to the cloth-making line after a specified number of picks have 90 been thrown in, and for this purpose the eccentric is given a forward movement just before the lay moves on its beat to drive all the picks home and cause the terry-warp threads to rise 95 and form loops. A cam, e', on the shaft e accomplishes this movement, being arranged to depress the lever G at the proper moment against the tension of the spring, and causes the eccentric through the connections to assume the position shown in Fig. 3 for a tight 100 beat. This alternate action of the spring and

cam upon the lever G effects the weaving of the terry piles or loops continuously. I apply my automatic devices to act upon the lever G, so that the force exerted by the spring to 5 throw the eccentric to its rearward limit after the completion of the terry may be resisted in order that the parts may remain in their forward position, so that one or more terry-loops can be missed, as desired, to produce the pattern.

I have shown in Figs. 1, 2, and 3 pattern mechanism designed to make and miss a terry, and thus weave a regular pattern, and in Figs. 4 and 5 is represented mechanism capable of 15 producing a variety of designs, and in which the recurrent sections of terry and plain weaving may be of different sizes, if desired. I will proceed to describe first the simpler construction, so as to lead to a better understanding 20 of the mechanism last referred to.

The lever G is provided with an extension, which has formed in its end a notch adapted for the reception of the pawl K', pivoted on one side of the girt A' of the machine. This 25 pawl is controlled by the pattern mechanism now to be described. D is the pick-shaft of the loom, to which power is applied in the usual manner. Upon it is keyed a pinion, 2, through which and the gear 3 is driven the 30 cam-shaft e. In a suitable bearing formed upon the girt and opposite the gear 3, Fig. 3, is journaled a pattern gear-wheel, 4, also driven by the pinion 2. A lever, 5, is pivoted to a suitable standard on the girt at a point near 35 the upper periphery of the wheel and in convenient position to be struck by a pin, 6, on one of the pattern-wheel spokes. The lower end of the said lever is connected by means of the cord or wire 7 to a second lever, x, placed 40 on the floor, and from this lever connection is made to the pawl through cord or wire 8 and arm 9. A spring of suitable strength is placed 45 in the connection 8. It will be understood that when the lever G is in the position shown in Fig. 2, and the pin on the gear 4 is not in engagement with the lever 5, the pawl will then be held by a suitable spring in its normal position—that is, directly in the path of the end of arm K—and as the said arm is raised, in 50 consequence of the cam on shaft e operating to throw the eccentric forward for the full beat of the lay, the end of said arm K will strike the pawl, ride over the same by reason of the spring 10 giving, and be caught and held as 55 the cam completes the depression of the lever. This will cause a terry-loop to be missed, and the weaving will be plain until the revolution of the gear 4 causes the pin to act upon lever 5 and throw the pawl from engagement with the 60 arm K, when the spring M will act and the parts be returned to form the terry. The picking-shaft D carries two arms, which act alternately to operate the pickers at the opposite ends of the lay in the usual manner. The shaft 65 e makes one revolution to one and a half revolution of the pick-shaft, and it will thus be

seen that after each third pick the eccentric will be thrown forward to make the lay beat home, and at the same time this movement is effected the pawl snaps into place and keeps 70 the lay beating home after each pick. The gear 4 is timed to make one revolution to two of the cam on shaft e, and the pin is positioned so that the pawl will be disengaged simultaneously with the second movement of the cam to 75 depress the lever, thereby permitting the parts to return to the former position for beginning the formation of the terry.

In Figs. 4 and 5 are shown the devices designed for a fabric different in design from that 80 produced by the above mechanism. In this form the parts are so timed and the pattern-chain will admit of so many variations that either a regular pattern, composed of a number of terries and a like-sized plain portion 85 may be woven, or a varying pattern, the sections of which may be composed of unequal numbers of terries. Motion is imparted to the catch or pawl K' through the rope or wire and lever-connections, as above described, 90 from a lever, y, supported pivotally at point 11 on the frame. This lever has a horizontal portion provided with a downwardly-projecting end, 12, adapted to be raised and lowered by the pins of a pattern-chain, W. The 95 chain is suitably supported upon a wheel, w, having its bearings in the girt A' in a manner similar to that of the gear-wheel 4. A pawl-and-ratchet mechanism is employed to actuate this chain. The ratchet is shown at 100 13 and its pawl at 14. A slide-bar, 15, is used to carry the pawl, and is supported on the journal of the pattern-wheel and at point 16 from the frame, being slotted, as shown, to permit longitudinal movement. Motion to 105 the slide-bar is given in one direction by means of a cam, e², on the shaft e and the projecting arm 18 from the slide-bar. In the opposite direction the movement is effected by means of the spring 19. (Shown in Fig. 4.) Obviously the cam e² may be changed to operate the bar 15 both backward and forward by means of a cam-groove adapted to receive a pin from said bar or through the medium of a strap from the bar embracing the cam. 115 These devices are, however, merely the equivalent of the cam and spring above described.

Suppose a fabric is to be produced, the pattern of which is composed of a number of terries woven without a miss, followed by a 120 plainly-woven portion of fabric. In order to do this, it is necessary that the pawl K' should be thrown out of the path of the end K of the lever G, when the said end is falling after the completion of the formation of the terry-loop, 125 so that the terry motion will be continued without a miss, the position of the pawl K' allowing the said end K of the lever to fall freely for this purpose. The cam for operating the pawl slide-bar is arranged to act in 130 unison with the cam for depressing the lever G, and it will thus be observed that the pat-

tern-chain makes one movement every time the said lever is depressed. Now, the pins of the pattern-chain may be so positioned that as the end K of the lever G rises, a pin 5 on the chain will act upon the end of lever y, raising it, and through the connections throwing back the pawl from engagement with the notch. The number of terry-loops successively woven will of course depend en-
10 tirely upon the position of the pins. Thus, if the pins are situated so as to act upon the lever y for each of five successive operations of lever G and pawl 14, the catch K' will not engage with the arm K during this time, and
15 consequently five terry-loops will be formed without interruption. Upon reaching a space from which a pin has been omitted the lever will act to keep the catch in its normal position in the path of the arm K, and upon the
20 next rise of said arm the catch will hold the parts so that the lay will beat home and weave plain fabric, this operation continuing until another pin is brought into action. This last-described mechanism can be used, of course, to
25 accomplish the same result as that effected by the first-described form. In this case the pins of the chain are arranged to actuate the lever once for each two revolutions of the shaft e.

It will be readily understood that the various details of connections, bars, arms, &c., between the essential operating parts can be varied as mechanical skill may dictate without departing from the spirit of my invention.

I claim as my invention—

30 1. In combination, the lay, a crank-shaft connected to said lay by pitmen, movable eccentric bearings for said crank-shaft, a rock-shaft, D, connections between said rock-shaft

and the eccentric bearings, a lever, G, for operating said rock-shaft and connections between 40 the lever and shaft, means for operating the lever G, a pawl held under tension for engaging the end of said lever, and pattern mechanism for operating said pawl to control the beat of the lay, substantially as described. 45

2. In combination, the lay, the crank-shaft therefor, the pitmen, the movable bearings for said shaft, the lever G, the cam e', for operating the lever, connecting mechanism consisting of arms, links, &c., substantially as de- 50 scribed, between the said lever and the movable bearings, a catch or pawl adapted to act upon said lever G, a pattern mechanism, a lever operated thereby, the connections 7 and 8, and the supplemental lever x for operating 55 the said pawl, all substantially as described.

3. In combination, the lay, the crank-shaft, the pitmen, the movable bearings for said shaft, the lever G, the cam e', for operating the same, connecting mechanism consisting of 60 arms, links, &c., substantially as described, between the said levers G and the movable bearings, the pawl or catch, the lever y, the connections between said pawl and said lever y, the pattern-chain, the pawl and ratchet, the operating-bar 15, the spring and cam e' there- 65 for, and the shaft e, the said cams e' and e' being arranged to act in unison, substantially as de- scribed.

In testimony whereof I have signed my name 70 to this specification in the presence of two sub- scribing witnesses.

FRANK LEAKE.

Witnesses:

ALBERT W. COX,
EDWARD S. MCINTYRE.
